 field, N. J., a corporation of New Jersey

Application September 26, 1944, Serial No. 555,876

9 Claims. (CL. 62—1)

1

This invention relates to the storage of normally gaseous phase changeable material, and particularly to a method and apparatus for liquefying such material in solid phase, storing the liquefied material and controlling the temperature thereof by a reversible cycle refrigerating system.

In storing a normally gaseous phase changeable material, such as carbon dioxide and the like in large quantities, in one container, it is desirable to refrigerate the stored material to maintain it at a low temperature and at a corresponding low pressure, whereby the wall thickness of the container may be reduced, with consequent advantages, such as saving in weight, material and cost.

In accordance with this invention, it is proposed to charge a relatively large storage container with material such as solid carbon dioxide, and to liquefy the charge for storing the same in the container at a low temperature and its corresponding vapor pressure. It has been found that a reversible cycle refrigerating system or unit may be utilized for this purpose, wherein, during operation in one direction, hot refrigerant serves to effect liquefaction of the solid carbon dioxide and, during operation in the opposite direction, cold refrigerant serves to maintain the liquid carbon dioxide at its predetermined low temperature.

Accordingly, an object of the invention is to provide a method and apparatus for liquefying and/or storing normally gaseous phase changeable material in a more effective way than heretofore practiced.

Another object is to more effectively liquefy and store a large quantity of such material in a single container.

Another object is to provide a system or apparatus wherein the refrigerant employed in the course of supplying heat to liquefy solid material thereafter maintains the liquefied material at a predetermined temperature.

Another object is to provide a storage chamber or tank especially adapted to receive solid material without damage to the tank.

Another object is to provide a tank or storage chamber having heat exchange means therein adapted to more effectively operate both as an evaporator and a condenser in removing heat from and supplying heat to the stored material.

A further object is to provide a system or apparatus of the above indicated character which is simple and durable in construction, economical to manufacture and effective in its operation.

2

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Figure 1 is a diagrammatic view, illustrating an embodiment of a system or apparatus, in accordance with the invention, for practicing the method thereof.

Figure 2 is a sectional view of a novel storage tank employed in the system, parts being shown in full and others being broken away.

Figure 3 is a diagrammatic view of a modification of the invention as shown in Figure 1.

Figure 4 is a view similar to Figure 3 of the invention in further modified form.

25 *The system in general*

Referring to Figure 1, a reversible cycle refrigerating system, for practicing the method of the invention, comprises a conduit circuit including valves 1 to 15 inclusive, in which circuit are disposed, heat exchange means such as a coil 17 positioned in a storage chamber, structure or tank 16, heat exchange units 18 and 19, an expansion valve 20, a liquid receiver 22, a dehydrator 23, an expansion valve 24, heat exchange means 26 having a fan 27, a refrigerant compressor 28, and pressure gauges 29 and 30.

The valves 1 to 15, inclusive, as shown, are of the hand operated type and are adapted to be manipulated to condition the circuit for its cycles of operation. If desired, the valves may be operated automatically by suitable control means such as a fluid pressure medium or electrical circuit to effect reversal of the cycles of operation.

45 The expansion valves 20 and 24, of Figure 1, are of the automatic, or fixed orifice, type.

46 *The system in detail*

In the system, the coil 17 is connected from 50 its lower end by a conduit 32 to the valve 1, through a conduit 34 to the valve 2, and through a conduit 36 to the liquid receiver 22. From the latter, the conduit system extends through a conduit 37 to the dehydrator 23, through a conduit 38 to the valve 3, through a conduit 40

to the expansion valve 24 and the valve 4, through a conduit 42 to the valve 5, through a conduit 44 to the valve 6, and through a conduit 46 and the heat exchange units 18 and 19, to the upper end of the coil 17.

The valve 11 is connected by a conduit 48, at one side, to the conduit 46, and at the other side, by a conduit 50 to the valve 10. The valve 10 is connected by a conduit 52 to the valve 9, which is connected by a conduit 54 to the conduit 36.

The valve 7 is connected by a conduit 56 to the conduit 32, and to the expansion valve 20 by a conduit 58, the valve 20 being connected by a conduit 60, to the valve 8 which is connected by a conduit 62 to the conduit 38.

The compressor 28 is connected, at one side by a conduit 64, to the conduit 50, and at the other side by a conduit 66 to the conduit 44. The pressure gauges 29 and 30 are connected in the conduits 64 and 66 at opposite sides of the compressor, respectively.

The heat exchange means 26 is connected by conduits 68 and 70 between the conduits 42 and 52.

The heat exchange unit 18 is connected, at one side, by a conduit 76, to the valve 12 which is connected by a conduit 78 to the conduit 32, and, at the other side, by a conduit 80, to the valve 13, which is connected by a conduit 82 to the conduit 34. The heat exchange unit 19 is connected at one side by a conduit 86 to the valve 15, which is connected by the conduit 80 through the valve 13 and the conduit 82 to the conduit 34. The other side of the unit 19 is connected by a conduit 88 to the valve 14 which is connected by a conduit 90 to the conduit 34.

The above described conduits are for illustrative purposes only, it being obvious that they may be otherwise arranged to accomplish the same function.

The tank

Referring to Figure 2, the tank 16 comprises a base structure 92 including legs 94, feet 96 and cross brace means 98, the legs being fitted at the upper ends, as by curved portions 100, to a bottom element 102 of an upright outer shell 103 having a cylindrical side wall 104, into the top of which depends a cup-shaped closure element 106, the parts of the tank, as thus far described, preferably being formed of metal and secured together as by welding.

An inner shell 110 is disposed within the outer shell, and constitutes the storage chamber for the material. The shell 110 comprises a top member 112, cylindrical side wall section 114, and a bottom member 116, the top member 112 and the bottom member 116 being welded to the side wall section 114 at 118 and 120, respectively.

The inner shell 110 is of sufficiently smaller diameter than the outer shell 103 to provide an effective insulating space 122, shown, in this instance, as a vacuum space for certain applications, or which may contain suitable insulating medium or the like.

The top member 112 of the inner shell 110, and the top closure element 106 of the outer shell 103, have adjacent registering apertures of substantially oval or elliptical shape, on the minor axis of which the section of Figure 2 is taken. An oval sleeve 124 is positioned in these apertures and is welded to the member 112 and the element 106 in sealed relation thereto. The sleeve 124 provides an oval opening through which solid material may be placed into the inner shell, and

forms a downwardly facing shoulder 126 for a cover 128 conforming to the contours of the oval parts set forth, and having a seat 130 for a sealing gasket 132 adapted to engage the shoulder 126.

The cover 128, in cross section, is bowed upwardly to conform to the arch at the top of the inner shell 110, and has an internally screw threaded aperture portion 134 for the reception of a relief valve 136.

A clamp member 138, of which there may be one or more, spans a portion of the oval aperture of the sleeve 124. The member 138 engages the sleeve 124 and is connected to the cover 128, as by a bolt or bolts 140, each having a nut 142 thereon for clamping the cover 128 in closed position.

A metal ring 146, of angle section, is secured as by welding, in position in the top closure element 106 to form a seat 148 for a sealing gasket 150 on which is disposed a top insulating cover 152.

The cover 152 is of hollow wall character, containing an insulating filler 154, and comprises upwardly arched top and bottom wall elements 156 and 158, respectively, both of thin sheet metal, and the top element 156, which is of simple inverted substantially cup-shape, is welded at its bottom edge, to the top side of the bottom element 158. The bottom element 158 has an outer peripheral flat horizontal margin 160 forming a shoulder for cooperation with the gasket 150. The cover 152 rests by gravity in closed position, as illustrated, and is provided with handle means 159, as indicated in Figure 1.

At the bottom of the shell 110, a metal hood 162, made up of a disc top portion 164, and a cylindrical side wall portion 165 welded to the portion 164 and having openings 166, is provided for the top end of a discharge pipe 168 extending through the bottom member 116 and the bottom element 102 and welded thereto. A brace 170 is provided between the discharge pipe 168 and the bottom member 116, and a similar brace 172 between the discharge pipe and the bottom element 102, and a cap, closure valve or other element 174 is provided at the lower end of the discharge pipe 168.

The coil means

The coil 17, as shown in Figure 2, comprises an upper nipple 176 bridging the insulating space 122 and extends through apertures in the inner cylindrical section 114 and the side wall 104 of the outer shell, in which apertures it is welded and sealed. The outer end of the nipple 176 is internally screw threaded for attachment to the conduit 46, and the inner end of the nipple 176 is adapted for the reception of a substantially single turn coil section 178 of metal tubing having its coil diameter nearly equal to the internal diameter of the inner cylindrical section 114. The lower end 179 of the coil section 178 is attached, as by coupling means 180, to an upright pipe section 182, of substantial length, but only fragments of the top and bottom end sections of which are shown.

The lower end of the upright pipe section 182 is similarly connected, as by coupling means 184, to the upper end 186 of a lower coil section 188 having, in this instance, about twelve turns. The lower end 190 of the coil section 188 is connected to a nipple 192, similar to the nipple 176 in its relation to the inner cylindrical section 75 114, the insulating space 122 and the outer side

wall cylinder 104, and also having an outer end, similar to the outer end of the nipple 176, for attachment to the conduit 32.

A metal sleeve-like shield 194, having a diameter smaller than the diameter of the coil section 188, is disposed inside the coil section to protect the latter from damage by impact with, or the weight of, the charge of solid carbon dioxide to be disposed therein.

The upper single turn coil section 178 and the lower multiple turn coil section 188 are thus arranged in accordance with the condition of the refrigerant, as it comes in warm condition from the high side of the compressor 28.

The coil section 178 at the upper portion of the tank provides for some heat transfer at or near the liquid level in the tank, while the coil section 188 at the lower portion of the tank provides for the bulk of the heat transfer to take place at the lower portion of the tank where the solid carbon dioxide is disposed during the latter period of the heating cycle and where the liquid is located during storage. This arrangement gives the best heat transfer to meet all conditions of use of the apparatus and is particularly advantageous during the heating cycle.

Operation

HEATING CYCLE

For the heating cycle, valves 1, 2, 3, 4, 6 and 10 will be open, and the valves 5, 7, 8, 9, 11, 12, 13, 14, and 15 will be closed.

In operation, to convert the solid material in the tank 16 to liquid state, and starting at the high pressure side of the compressor 28, with valve 5 closed and valve 6 open, compressed hot refrigerant vapor passes from the compressor 28, through the conduits 66 and 44, the valve 6 and the conduit 46 to the nipple 176.

From the latter, the hot refrigerant passes through the single turn coil section 178, the upright pipe section 182 and the lower coil section 188, where heat is given up, as aforesaid, and the refrigerant is condensed to a liquid by the low temperature of the solid material (about -110° F. when storing carbon dioxide). This heat exchange means in the foregoing instance acts as a condenser.

With the valves 7, 8, 9, 12, 13, 14 and 15 closed, and valves 1, 2, 3 and 4 open, the cold liquid refrigerant travels through the lower nipple 192, the conduit 32, the valve 1, the conduit 34, the valve 2, and the conduit 36, to the liquid receiver 22. From the liquid receiver 22, the liquid refrigerant passes through the conduit 37 to the dehydrator 23, and, with the valve 8 closed and the valve 3 open, the liquid is expanded through the expansion valve 24 into the heat exchange means 26 which acts as an evaporator in the material heating cycle.

The expanded refrigerant is heated in the heat exchange means 26 by air blown thereon by the fan 27 and, with valves 9 and 11 closed, and the valve 10 open, the refrigerant passes to the low pressure side of the compressor 28 to complete the heating cycle.

During the heating cycle, by opening the valves 12, 14 and 15, and closing the valves 1 and 13, the cold condensed refrigerant will be heated by heat from the hot refrigerant vapor in the conduit 46 passing through both of the heat exchange units 18 and 19 to thereby control the temperature of the cold refrigerant and to maintain it above a predetermined minimum to pre-

vent damage to the compressor 28 and frosting of the heat exchange means 26. If less heat is required, the valves 14 and 15 may be closed and the valve 13 opened to cut the unit 19 out of the circuit and retain the heat of the unit 18 in the circuit, thus illustrating the selectivity and flexibility of the system in this regard. It will be understood that instead of the heat exchange units 18 and 19, means may be provided for supplying heat externally of the circuit to the cold refrigerant before entering the compressor.

COOLING CYCLE

For the cooling cycle, the valves 5, 7, 8, 9 and 11 will be open and the valves 1, 2, 3, 4, 6, 10, 12, 13, 14 and 15 will be closed.

To maintain the material as liquefied by the above-described operations, at a low temperature and corresponding pressure, starting at the high pressure side of the compressor 28, and with the valves 2, 4, 6 and 10 closed, and the valves 5 and 9 open, the refrigerant passes from the compressor through the conduit 66, the conduit 44, the valve 5, the conduit 42, the heat exchange means 26 now acting as a condenser, the conduit 70, the conduit 52, the valve 9 and the conduit 36, into the liquid receiver wherein the cooled condensed refrigerant is collected.

The cooled refrigerant passes from the receiver 22 through the conduit 37, through the dehydrator 23 and with the valve 3 closed, and the valve 8 open, the liquid passes through the conduit 62 and the valve 8 to the expansion valve 20, whereupon, with valve 7 open, and valves 1 and 12 closed, the liquid passes through the nipple 192 to the coil means 17 in the tank 16 where the expanded refrigerant removes heat from the liquid material. With the valve 11 open, and the valve 6 closed, the expanded refrigerant leaving the coil means 17, passes through the nipple 176, the conduit 46, and valve 11, the conduit 50 and the conduit 64 to the suction side of the compressor 28, to complete the refrigerating cycle.

After the above-described cooling cycle has been set up as stated, the liquid material is automatically maintained at a predetermined temperature by means, such as a switch, controlled by a pressure responsive device connected to the tank 16 near its discharge end, for opening and closing the motor circuits of the fan 27 and the compressor 28.

The system shown in Figure 3

Referring to Figure 3, in which corresponding parts are designated by corresponding reference characters the system is substantially the same as in Figure 1, except that the refrigerant always flows in the same direction through the coil 17. This result is obtained with only slight changes from the arrangement of Figure 1, such as the omission of the conduit 48, and the rearrangement of the conduit 50, the valve 11, the conduit 62, the valve 8, the expansion valve 20 and the valve 7, as will fully appear in the following description of the heating and cooling cycles.

For the heating cycle, valves 1, 2, 3, 4, 6 and 10 will be open, and the valves 5, 7, 8, 9, 11, 12, 13, 14 and 15 will be closed.

In operation, starting at the high pressure side of the compressor 28, compressed hot refrigerant vapor passes from the compressor, through the valve 6 and the conduit 46 to the upper end of the coil 17. From the bottom end of the coil 17, the condensed cooled refrigerant

travels through the valve 1 and the valve 2 to the liquid receiver 22. From the latter, the liquid refrigerant passes through the dehydrator 23 and the valve 3, is expanded through the valve 24 and passes through the valve 4 into the heat exchange means 26. From the heat exchange means 26, the refrigerant passes through the valve 10 to the compressor 28 to complete the heating cycle.

For the cooling cycle, the valves 1, 5, 7, 8, 9 and 11 will be open, and the valves 2, 3, 4, 6, 10, 12, 13, 14 and 15 will be closed.

Starting at the high pressure side of the compressor 28, the refrigerant passes from the compressor, through the valve 5, the heat exchange means 26, the conduit 52, and the valve 9 into the liquid receiver 22. The cooled refrigerant passes from the receiver 22, through the dehydrator 23, the conduit 62, the valve 8, the expansion valve 20 and the valve 7 to the upper end of the coil 17. From the lower end of the coil 17, the heated refrigerant passes through the valve 1, the valve 11 and the conduit 50 to the suction side of the compressor 28, to complete the refrigeration cycle.

After the above-described cooling cycle has been set up, the liquid material is automatically maintained at a predetermined temperature, as by the switch and pressure responsive device mentioned in connection with Figure 1.

The system shown in Figure 4

Referring to Figure 4, in which corresponding parts are designated by corresponding reference characters, the system is similar to those of Figure 1 and Figure 3, with one exception residing in the substitution of thermostatic expansion valves 196 and 198 for the automatic or fixed orifice expansion valves 20 and 24, respectively, and a consequent exception in the omission of the heat exchange units 18 and 19, the valves 12, 13, 14 and 15, and accompanying conduits.

A thermostatic bulb 200, associated with the conduit 34, is connected by a conduit 202, to the expansion valve 196, and a thermostatic bulb 204, associated with the conduit 52, is connected, by a conduit 206, to the expansion valve 198.

For the heating cycle, the valves 2, 3, 4, 6 and 10 will be open, and the valves 5, 7, 8, 9 and 11 will be closed.

Starting at the high pressure side of the compressor 28, the hot refrigerant passes through the valve 6, and the conduit 46 to the upper end of the coil 17. From the bottom of the coil, the cool refrigerant travels through the valve 2 to the liquid receiver 22, and from the latter through the dehydrator 23 and the valve 3 to the expansion valve 198. Expanded in the latter, the refrigerant flow continues through the valve 4, the heat exchange means 26 and the valve 10 to the suction side of the compressor 28, to thus complete the heating cycle.

For the cooling cycle, the valves 5, 7, 8, and 9 and 11 will be open, and the valves 2, 3, 4, 6 and 10 will be closed.

Starting at the high side of the compressor, the refrigerant passes through the valve 5, the conduit 42, the heat exchange means 26, the conduit 52, and the valve 9 to the liquid receiver 22. From the latter, the refrigerant passes through the dehydrator 23, the valve 8, the conduit 62, the expansion valve 196 and the valve 7 to the upper end of the coil 17. From the lower end of the coil 17, the refrigerant flows through the conduit 34, the valve 11 and the conduit 50

to the suction side of the compressor 28, to complete the cooling cycle, which may thereafter be automatically effected as above pointed out.

It will be seen, from the foregoing description, that the present invention provides an improved method and apparatus, whereby a large quantity of a normally gaseous phase changeable material may be stored, in the liquid state, in a single container or tank, the material being introduced to the tank as a solid. The latter feature has many advantages of handling the material both before and during the operation of charging the container. A simplified reversible cycle refrigerating system is advantageously utilized, both for liquefying the solid material, or changing the temperature of liquid material at the time of charging, and thereafter maintaining the liquid at a predetermined temperature and vapor pressure best adapted for such storage. Further advantages are thereby obtained, such as a reduction in weight, number of parts and cost of the assembly as a whole. The apparatus is easy to manufacture, assemble and operate, is a compact self-contained unit, and is durable and reliable in service.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described, and all statements of the scope of the invention which, as a matter of language might be said to fall therebetween.

I claim:

- 40 1. In a system for liquefying solid normally gaseous phase changeable material and storing and maintaining the material in liquid phase at a predetermined temperature, the combination of chamber means adapted to receive a charge of solid blocks of said material and store the material in liquid phase, reversible cycle refrigerating means including heat exchange means in said chamber means for effecting heat exchange between hot refrigerant and solid material to effect liquefaction of the solid material and cooling of the refrigerant and for effecting heat exchange between cold refrigerant and liquefied material to effect cooling of the liquefied material to maintain it at a predetermined temperature, and means for transferring heat from the hot refrigerant entering said chamber means to the cooled refrigerant leaving said chamber means while the cycle is operating in a direction to effect liquefaction of the solid material.
- 45 2. In a system for liquefying solid normally gaseous phase changeable material and storing and maintaining the liquid material at a predetermined temperature, the combination of chamber means adapted to receive a charge of solid blocks of said material and store liquid material, reversible cycle refrigerating means including heat exchange means in said chamber means for effecting heat exchange between hot refrigerant and said solid material to effect
- 50 3. In a system for liquefying solid normally gaseous phase changeable material and storing and maintaining the liquid material at a predetermined temperature, the combination of chamber means adapted to receive a charge of solid blocks of said material and store liquid material, reversible cycle refrigerating means including heat exchange means in said chamber means for effecting heat exchange between hot refrigerant and liquid material to effect cooling of the liquid material, means for supplying heat to the cooled refrigerant while the cycle is operating in a direction
- 55
- 60
- 65
- 70

to effect liquefaction of the solid material, and means for controlling the amount of heat supplied by said last mentioned means.

3. In a system for liquefying solid phase changeable normally gaseous material and storing and maintaining the liquefied material at a predetermined temperature, the combination of means providing a chamber for storing said material; and reversible cycle refrigerating means including heat exchange means in said chamber and means whereby refrigerant flows in the same direction through said heat exchange means during the opposite cycles.

4. In a system for liquefying solid phase changeable normally gaseous material and storing and maintaining the liquefied material at a predetermined temperature, the combination of means providing a chamber for storing said material; and reversible cycle refrigerating means including heat exchange means in vertical position in said chamber and means whereby refrigerant flows through said heat exchange means from an upper to a lower portion thereof during each of said cycles.

5. In a system for liquefying solid normally gaseous phase changeable material and storing the liquefied material, the combination of an upright tank adapted to receive the solid material and to store the liquefied material therein, reversible cycle refrigerating means including a cylindrical heat exchange coil in said tank adjacent the inner side wall thereof, said coil having a greater number of convolutions at the bottom than at the top of said tank, and a cylindrical shield within the lower portion of said coil for protecting the same against damage by impact from solid material when charging said tank therewith.

6. The method of handling normally gaseous phase changeable materials, which comprises establishing a supply of said material in solid phase, condensing a fluid heat exchange medium while in thermal contact with said supply to liquefy the material, and thereafter evaporating said heat exchange medium while in thermal contact with said supply to withdraw heat leaking into the supply of material from its surroundings and thereby maintain the liquefied material at a predetermined temperature.

7. A method of handling normally gaseous phase changeable materials comprising establishing a storage supply of solidified material in a confined zone, circulating a refrigerant in heat exchange relation with the supply of material while said refrigerant is vaporized and conditioned to add heat to the material to thereby cause the material to be liquefied and the refrigerant to be condensed, and thereafter circulating the condensed refrigerant in heat exchange relation with the supply of liquefied ma-

terial in the confined zone while said condensed refrigerant is conditioned to be evaporated and withdraw the heat leaking into the stored liquefied material from its surroundings and thereby maintain the liquefied material in the confined zone at a substantially constant temperature and pressure.

8. A method of handling carbon dioxide comprising establishing a storage supply of solid carbon dioxide in a confined zone, circulating a refrigerant in heat exchange relation with the solid carbon dioxide while said refrigerant is vaporized and conditioned to add heat to the carbon dioxide to thereby cause the material to be liquefied and the refrigerant to be condensed, and thereafter circulating the condensed refrigerant in heat exchange relation with the supply of liquefied carbon dioxide in the confined zone while said condensed refrigerant is conditioned to be evaporated and thereby withdraw the heat leaking into the liquefied carbon dioxide from its surroundings and thereby maintain the liquefied carbon dioxide in the confined zone at a substantially constant temperature and pressure.

9. The method of liquefying solid normally gaseous phase changeable material and storing and maintaining the liquefied material at a predetermined temperature, which comprises confining a charge of solid material in an enclosure, effecting heat exchange between hot refrigerant and the confined solid material to effect cooling of the refrigerant and liquefaction of the material to produce a confined charge of liquefied material in the enclosure, and thereafter effecting heat exchange between cold refrigerant and the liquefied material while confined in the enclosure to maintain a confined charge of liquefied material in the enclosure at a substantially constant temperature and pressure.
